The ornamental design for a cabinet, as shown and described.

DESCRIPTION

FIG. 1 is a top perspective view of a cabinet showing my new design;

FIG. 2 is a front elevational view thereof;

FIG. 3 is a left side elevational view thereof; the right side being a mirror image of the left side shown;

FIG. 4 is a top plan view thereof;

FIG. 5 is a rear elevational view thereof;

FIG. 6 is a bottom plan view thereof; and

FIG. 7 is a perspective view of a second embodiment of the cabinet shown in FIG. 1, the wavy lines on the cabinet represent wood grain;

FIG. 8 is a front elevational view thereof; and,

FIG. 9 is a left side elevational view, the right side being a mirror image.
